(57) **CLAIM**

The ornamental design for a massaging bath mat with air bubble generating unit, as shown.

DESCRIPTION

FIG. 1 is a front view of the present design;
FIG. 2 is a back view of the design;
FIG. 3 is a left side view of the design;
FIG. 4 is a right side view of the design;
FIG. 5 is a top view of the design;
FIG. 6 is a bottom view of the design; and,
FIG. 7 is a perspective view of the design.
